UNITED STATES PATENT OFFICE.

NATHAN M. LOWER, ALBERT R. CHALKER, AND LONNIE EDWARD OSBORNE, OF PITTSBURGH, PENNSYLVANIA, ASSIGNEES TO LOCOMOTIVE STOKER COMPANY, A CORPORATION OF PENNSYLVANIA.

GRATE SHAKER.

Application filed January 22, 1925. Serial No. 3,914.

To all whom it may concern:

Be it known that we, NATHAN M. LOWER, ALBERT R. CHALKER, and LONNIE EDWARD OSBORNE, citizens of the United States, and residents of Pittsburgh, county of Allegheny, and State of Pennsylvania, have invented certain new and useful Improvements in Grate Shakers, of which the following is a specification, and which is illustrated in the accompanying drawings, forming a part thereof.

This invention relates to grate shaking devices or mechanism for shaking the grates of locomotives and the like.

One of the objects of the invention is the provision of new and improved power and manually operated mechanism for operating or shaking the grates of a fuel burning furnace or firebox.

Another object of the invention is the provision of new and improved means for operating a selected section or portion of the grates either manually or by power means at the will of the operator.

A still further object of the invention is the provision of new and improved means for operating a grate shaking mechanism from the stoker motor.

Other objects of the invention are the provision of a grate shaking mechanism that is simple in construction, efficient in operation, cheap to manufacture, easily assembled and that consists of few moving parts.

Other and further objects and advantages of the invention will appear from the following description taken in connection with the accompanying drawings, in which

Fig. 1 is a rear elevation of a portion of a locomotive with parts in section, and with parts of the stoker omitted for the sake of clearness;

Fig. 2 is a vertical section thereof on line 2—2 of Fig. 1;

Fig. 3 is a horizontal section of a portion of the firebox substantially on line 3—3 of Fig. 1, showing the grate operating mechanism in position thereon, with parts omitted for the sake of clearness;

Fig. 4 is a section on line 4—4 of Fig. 1, with parts omitted;

Fig. 5 is a view similar to Fig. 2, showing the clutch mechanism, and with parts omitted:

Figs. 6 and 7 are perspective views of details of the operating mechanism.

On the drawings the reference character 1 designates the firebox of a power plant, as a railway locomotive, having the rear wall 2 in which is the fire door opening 3. The locomotive is provided with stoker mechanism which may be of the usual or any well known construction, and comprises a fuel conveyor 4 and elevator mechanism 5 for conveying the fuel from the tender and delivering the same to the distributor tube 6 from whence it is projected into the firebox in a manner common in the art. The conveyor and elevating mechanism are adapted to be operated by a reciprocating motor 7. As is usual in this type of stoker, the conveyor operating shaft 8 is provided with a pinion 9 which is adapted to be oscillated by the rack 10 on the rackbar 11. The bar 11 is reciprocated by the piston of the motor 7, to which it is connected. The elevators of which there are usually two are operated by the rack 13 on the rack bar 11 in the usual manner. Since the details of the stoker mechanism constitute no part of the present invention, it is not thought necessary to illustrate or further describe the same.

The grate is divided into sections, and suitable means are provided for independently operating each section. The grates are divided longitudinally along the median line of the firebox and are also divided transversely thereof to form the forward left and right sections 14 and 15, and the rear left and right sections 16 and 17, respectively. The left and right dump sections 18 and 19 constitute the rear portion of the grate.

The left and right dump grate members 18 and 19 pivoted as at 21 constitute the extreme rear portions of the grate area of the firebox. The grate members 18 and 19 are operated independently by the levers 22 and 23, respectively. The levers 22 and 23 are pivoted intermediate their ends to suitable brackets 24 and 25 secured to the rear side of the rear wall of the fire box. Links 26 and 27 are pivotally connected to the lower ends of the levers 22 and 23, respectively, whereby the dump grate members may be operated by said levers. The levers may be secured in operative position by any suitable means, such as the bolts 28 and 29 slidably

mounted in the brackets 30 and 31 carried by the deck and which are adapted to engage suitable openings in the levers 22 and 23.

The grate bars of each section are pivotally connected together by connector bars 32, see Figs. 2, 3 and 4, whereby all the grate bars of one section may be oscillated together to the exclusion of the remaining sections. The connector bars 32 are adapted to be oscillated by any suitable means. As shown, the rear left and right grate sections are adapted to be operated by shaker rods or links 33 and 34 which are pivotally connected at their forward ends to the connector bars 32 as at 35 and 36, respectively, see Fig. 3. The forward sections 14 and 15 of the grate are operated by the shaker rods or links 37 and 38 which are pivotally connected to the connector bars 32 as at 39 and 41, respectively.

The grate bar sections are so arranged that they may be operated either simultaneously or independently. Furthermore, the construction is such that the grates may be shaken either by hand or by power operated mechanism at the will of the operator. Any suitable means may be employed for this purpose. In the form of the device selected to illustrate one embodiment 30 of the invention, the grate sections may be operated from the stoker motor in a manner that will now be described.

The inner end of the conveyor operating shaft 8 is provided with a worm 40 which engages a gear quadrant 42 on a counter-shaft 43 for oscillating the same. The worm is of such a pitch that it may be oscillated by oscillating the gear.

The shaft 43 is provided with a plurality 40 of arms 44 which are connected together by the actuating rod 45 forming an oscillating member.

Suitable means are provided for selectively connecting the links 33, 34, 37 and 38 to this actuating rod or oscillating member whereby as the rod is oscillated the grates connected to the same will be agitated or shaken. The rear portions of the shaker rods or links 33, 34, 37 and 38 are alike and each is provided with a notch 46, see Fig. 4, for engaging the oscillating member or actuating rod 45. Their rear ends are supported by the laterally bent lower ends 50 of the corresponding pull rods 47, 48, 49 and 51 respectively. The pull rods are provided with means for holding the same in either elevated or lowered position. As shown, each pull rod is provided with a lug 52, see Fig. 4, which is adapted to engage either the hook 53 or the hook 54 for holding the rod and its actuating bar in elevated or lowered position.

Suitable clutching means are provided for connecting or disconnecting the worm 40 with the shaft 8. The worm 40 is loose on

the power shaft 8 and its rear end is provided with a clutch tooth 55 which is adapted to engage a corresponding recess 56 in the clutch member 57 splined upon the shaft 8 as is usual in such constructions. The clutch member 57 is operated by the shipper lever 58 pivoted as at 59. The upper end of the lever is adapted to be held with the clutch disengaged by any suitable means such as the pin 61, see Fig. 1.

It is necessary that the actuating rod 45 be held in its uppermost position when at rest in order that the same may be engaged by the links 33, 34, 37 and 38 when they are lowered preparatory to shaking the grates. A lever mechanism is employed for this purpose. As shown, a lever 62 pivoted as at 63, see Figs. 4 and 5, is provided with a slotted extension 64 to which is pivoted the rear end of the retaining lever 65. The lever 65 is pivoted intermediate its ends as at 66 and its front curved end 67 is provided with a notch 68 which is adapted to engage the actuating rod 45 only when the latter is in its upright position.

The clutch lever 58 is operated from the hand lever 62. A spring 77, see Fig. 5, connects the levers 62 and 58 whereby when the lever 62 is moved rearwardly the lever 58 is also moved rearwardly, and at the same time thereby engaging the clutch. The lever 62 may be held in rearward position by pin 78 in the bracket 79, see Figs. 1 and 4.

By providing the spring 77 between the levers 58 and 62 the lever 62 may be moved rearwardly and secured in adjusted position at any time in the operation of the device. The spring will cause the tooth 55 to engage the recess 56 only when the latter has been rotated to a position opposite that of the tooth. The angle of the cooperating sides of the tooth and recess is such that the spring will permit the clutch tooth to ride up out of the recess should the normal movement of the grates become obstructed or locked for any reason during their operation, thereby preventing injury to the mechanism.

It is desirable that means be provided for preventing the disengagement of the clutch during the normal operation of the device at any time except when the grates are in horizontal position. Any suitable means may be employed for this purpose. In the form shown, the end 67 of the lever is so curved that when the clutch is engaged the actuating rod 45 will oscillate in such close proximity to the outer circumference of the curved end 67 that the lever 62 which operates the curved end 67 cannot be moved forwardly to disengage the clutch except when the rod 45 comes opposite the notch 68.

Each of the grate operating links is provided with suitable means, as the notch 69 in which the stop 71 is adapted to engage, for preventing longitudinal movement of

said links while in their inoperative position.

Suitable means are provided for locking the pull rods 47, 48, 49 and 51 in adjusted position while the actuating bar 46 is oscillating. As shown, a bell crank 72, see Fig. 4, operated by a link 73 from the lever 62 is provided with an arm 74 which is adapted to engage in either the notch 75 or the notch 76 for holding each pull rod in either elevated or lowered position. In other words, the pull rods will be locked in their adjusted position when the lever 62 is moved rearwardly.

Suitable means are also provided whereby the grate sections may be operated manually. As shown, the shaft 43 (see Fig. 1) is provided with an arm 81 to which the lower end of the lever 82 pivoted to the plate 24 is adapted to be connected as by means of the link 83 for oscillating said shaft. The oscillation of the shaft will oscillate the bar 45 and thereby shake any section of the grate that is connected to said bar. The grate sections are connected to the bar 45 by lowering the corresponding levers 47, 48, 49 and 51. In the manual operation of the grates, the pull rod or rods corresponding to the grate section or sections to be operated are lowered, the lever 62 moved rearwardly and secured to the bracket 79 to disengage the curved retaining member 67 from the actuating bar 45, after which said bar is oscillated by the hand lever 82. In operating the grates by the hand lever 82 the shipper lever 58 is held in inoperative position by the pin 61.

When the grates are to be operated by power, the pull rod or rods corresponding to the sections desired to be operated, are lowered, the clutch lever released from the pin 61, and the lever 62 moved rearwardly, which, through the action of the spring 77, will cause the engagement of the clutch. This rearward movement of the lever 62 will also disengage the notch 46 from the bar 45 and will lock the pull rods in adjusted position by the arm 74 of the bell crank 72 engaging in one or the other of the notches 75 or 76 in said pull rods.

The angle of the clutch tooth and recess is such that when the tension of the spring 77 is released by moving the lever 62 forward, the same will force the clutch member rearwardly to thereby disengage the clutch.

It will be evident that the forms and proportions of the parts and means of connection may be varied without departing from the main features of our invention.

Without limiting ourselves to the construction and arrangement shown, we claim—

1. In combination, a firebox, a grate comprising independently movable sections, a grate moving member, means for selectively detachably connecting said sections to said

member whereby said sections may be operated either independently or simultaneously, and means for operating said member.

2. In combination, a firebox, a sectional grate therefor, stoker operating mechanism, a member reciprocated by said mechanism, and means for selectively detachably connecting said grate sections to said member for operating said sections.

3. In combination, a firebox, a sectional grate therefor, stoker operating mechanism, a member reciprocated by said mechanism, means for selectively detachably connecting said grate sections to said member for operating said sections, and clutch means for detachably connecting said member to said mechanism.

4. In combination, a firebox, a sectional grate for said firebox, stoker mechanism including a power shaft for supplying fuel to said firebox, a bail member, means for oscillating said member from said power shaft, links connected to said grate sections and means for independently or simultaneously detachably connecting said links to said member for oscillating any or all of said grates.

5. In combination, a firebox, a plurality of grate sections within said firebox, stoker mechanism including a motor for supplying fuel to said firebox, and mechanism including a movable member for operating said sections from said motor, and means independent of said mechanism for selectively disconnecting said sections from said movable member.

6. In combination, a firebox provided with grate sections, stoker mechanism including a motor for supplying fuel to said firebox, and means for operating said sections from said motor, said means comprising an oscillating bail, links connected to said sections and means for detachably connecting said links to said bail for operating said sections.

7. In combination, a firebox, a plurality of grate sections within said firebox, stoker mechanism including a motor for supplying fuel to said firebox, means including an oscillating member for operating said sections from said motor, means for disconnecting said motor, means for manually operating said oscillating member, and means for selectively connecting said sections to said member.

8. In combination, a firebox, a plurality of grate sections within said firebox, and means for agitating said grate sections either manually or by power, at the will of the operator, said means comprising a movable bail member and means for detachably connecting said grate sections to said bail member.

9. In combination, a firebox, a sectional

- grate for said firebox, a power shaft, a bail, means for oscillating said bail from said power shaft, a clutch for controlling the operation of said bail, means for engaging said bail for selectively operating the sections of said grate, a lever, a bail engaging member operated by said lever, a clutch operating member and resilient means between said lever and said last named member for 10 operating said clutch on the movement of said lever in one direction.
10. In combination, a firebox, a grate section therefor, said section comprising a plurality of movable grate members, a power shaft, means for operating said section from said shaft, and means for preventing the disengagement of said first-named means except when said grate members are in horizontal position.
- 15 11. In combination, a firebox, a grate section therefor, said section comprising a plurality of movable grate members, a power shaft, means for operatively connecting said section to said shaft, means for preventing

the disengagement of said first-named means 25 except when said grate members are in horizontal position, and means for preventing movement of said grate members while they are in inoperative position.

12. In combination, a firebox, a plurality of grate sections therefor, a movable member, power means for operating said member, links secured to said sections for operating the same, a control member for each grate section for selectively detachably 35 connecting said links to said member, and a single lever for manually operating said sections.

13. In combination, a firebox, a plurality of grate sections therein arranged 40 laterally of each other, an oscillating member, power means for operating said member, means for detachably connecting said sections to said member, and means for manually operating said member. 45

NATHAN M. LOWER.
ALBERT R. CHALKER.
L. EDWARD OSBORNE.
